UNITED STATES PATENT OFFICE.

FRANÇOIS PILAIN, OF LYON, FRANCE.

TWO-STROKE CYCLE EXPLOSION-MOTOR.

1,074,894.

Specification of Letters Patent.

Patented Oct. 7, 1913.

Application filed December 31, 1912. Serial No. 739,500.

To all whom it may concern:

Be it known that I, FRANÇOIS PILAIN, a citizen of the French Republic, residing at Lyon, in France, have invented certain new and useful Improvements in Two-Stroke Cycle Explosion - Motors, of which the following is a specification.

This invention relates to improvements in two stroke cycle explosion motors.

10 The defective operation and low efficiency that has hitherto prevailed in two-stroke cycle explosion motors arise from difficulties in insuring the exhaust of the burned gases and the suction of fresh gas during 15 a small portion of the piston-stroke. The use of circulation channels of very large section partly reduces this inconvenience but as it is necessary to commence the suction before the end of the exhaust, this arrangement 20 is accompanied by the admixture of burned gases and fresh gases.

The object of the present invention is a so called "valveless" two stroke cycle motors which, while permitting the use of 25 channels of very large section prevents the mixture of burned gases with fresh gases by introducing the latter into the cylinder in the form of an annular column rising along the walls of the cylinder, while the 30 burned gases remaining in the cylinder after the commencement of the suction are exhausted in the form of a central descending column into a vacuum chamber to reach which said gases pass through channels in 35 the cylinder and piston.

The method of operation consists in producing the exhaust in two phases: The first period of exhaust is effected by ports arranged all around the cylinder, which are 40 uncovered by the piston, and during the second period of exhaust which commences with the suction, the charge is sucked into the cylinder through the ports which previously served for the exhaust, said ports 45 being alternately put into communication with the exhaust outlet and with the inlet pipe, by means of a sleeve surrounding the cylinder and acting with respect to said ports as a distributing valve.

50 The operation will be more readily understood by referring to the accompanying drawings in which,

Figure 1 is a vertical section through the axis of the cylinder with the parts in 55 position when the piston is at the end of the up stroke at the moment of ignition.

Fig. 2 is a similar view to Fig. 1 with the ports in position when the piston uncovers the exhaust ports. Fig. 3 is a similar view to Figs. 1 and 2 showing the position of various parts when the piston is at the end of its down stroke. Fig. 4 is a similar view to Figs. 1 to 3 showing the different parts in position at the commencement of the compression period. Figs. 5, 6 and 7 are transverse sections through the cylinder and piston on the lines 5-5, 6-6 and 7-7 respectively of Fig. 3.

The invention involves the use of two concentric and superposed cylinders *a* and *b*. The upper cylinder *a*, which is the working cylinder proper, passes partly into the lower cylinder *b*, the diameter of which is sufficient to leave an annular space *c* between said cylinders. The cylinder *a* has a series of annularly disposed ports *d* which afford communication between the interior of the cylinder and the space *c*, said ports being located at a height suitable to be uncovered by the piston *e* when the latter approaches the end of its down stroke. By reason of their arrangement annularly all around the circumference of the cylinder *a*, these ports provide a very large area for the passage of gas. The cylinder *b* is provided with an exterior annular jacket or chamber *f* which communicates directly with the space *c* and into which the explosive mixture enters by the tube *g*. Below said chamber *f* is a second chamber *h* serving as a collector for the exhaust gases which discharge therefrom through the pipe *i*. This chamber *h* communicates with the annular space *c* by means of ports *j* and *j'*.

In the cylinder *b* is a movable sleeve *k* which fits exactly in the annular space *c* between the two cylinders *a* and *b*. This sleeve is provided with longitudinal channels *l* opening by orifices *m* and *m'* into the cylinder *a* and issuing at *l'* into the cylinder *b* and further with ports *n* separated from the channels *l* by a bridge *o* and surmounted by a covering ring *p*. The sleeve is given a movement alternately in opposite directions by eccentric gear (not shown) driven by the motor shaft, and its movements cause the ports *d* of the cylinder *a* to alternately communicate with the chamber *f* through the ports *n*, and with the exhaust chamber *h* through the orifices *m* and ports *j* by means of the channels *l*. At other positions the

ports d are covered either by the bridge o or by the ring p . The piston e working in the cylinder a terminates below in a flange e^1 fitting tightly against the sleeve k and forming in the interior of the same a chamber q into which the suction of the burned gases is effected. The piston is also provided at its upper end with an annular rim r in the interior of which are channels s which terminate at the circumference of the piston and are adapted to communicate either with the aforesaid ports d or with channels t , formed lower down in the piston, by means of ports u formed in the wall of cylinder a .

15 The operation of the apparatus is as follows: At the moment of ignition, Fig. 1, the ports d are covered by the piston e and the latter commences its down stroke transmitting to the motor shaft v the expansive force 20 of the exploded gases, and bringing the channels s in register with the ports d in the position shown in Fig. 2. As at this moment the orifices m of the channels l are also in register with the ports d , a portion of 25 the burned gases pass directly to the exhaust chamber h through the ports j and are discharged through the pipe i . During this time the descent of the piston has produced a vacuum in the chamber q which is cut off 30 from all communication. The piston continuing to descend arrives at the end of its stroke (Fig. 3) in which position the ports d after having been covered by the piston itself and by the bridge o of the sleeve k are 35 again uncovered and place the inlet chamber f in communication with the interior of the cylinder. At the same time the vacuum chamber q is placed in communication with the cylinder through the channels s , u and t 40 and owing to the vacuum therein sucks into said chamber the burned gases still remaining in the cylinder. The suction thus produced in the cylinder causes an intake of fresh mixture above the piston this mixture 45 being directed upward in a vertical current by the rim r , in such a manner that the currents of fresh mixture, and of the burned gases remain independent of one another and have no tendency to mix.

50 The piston in rising does not cover the ports d until sufficient time has elapsed to allow the complete charging of the cylinder, that is to say, when it has reached the position shown in Fig. 4. At this moment the 55 solid ring p of sleeve k in descending closes said ports to prevent return of the gases in the cylinder to the inlet chamber f when the channels s uncover the ports d , while the orifices m^1 leading into the vacuum chamber 60 q cause the latter to communicate with the exhaust chamber h in order that the gases sucked into said chamber can be forced out by the flange e^1 of the piston and discharged into said exhaust chamber through the ports 65 j^1 . The piston on continuing to rise, com-

presses the charge in the cylinder until it has again reached its highest position (Fig. 1) whereupon a fresh explosion is produced.

What I claim as my invention and desire to secure by Letters Patent of the United States is:—

1. In a two stroke cycle explosion motor the combination of a cylinder having common intake and exhaust ports, a piston working in said cylinder adapted to cover and uncover said ports, an inlet chamber and an exhaust chamber exteriorly of said cylinder, a vacuum chamber between the piston and cylinder, a reciprocatable member adapted to place said ports alternately in communication with said inlet and exhaust chambers and means controlled by said reciprocatable member whereby part of the burned gases in the cylinder are passed into said vacuum chamber.

2. In a two stroke cycle explosion motor the combination of a cylinder having common annularly disposed intake and exhaust ports, a piston working in said cylinder adapted to cover and uncover said ports, an inlet chamber and an exhaust chamber interiorly of said cylinder, a reciprocatable sleeve surrounding the cylinder adapted to place said ports alternately in communication with said inlet and exhaust chambers, means on the piston for causing gases admitted through said ports to assume an annular column along the walls of the cylinder, and means whereby burned gases may be exhausted from the cylinder in a central descending column separate from the incoming column and through the piston and said ports.

3. In a two stroke cycle explosion motor the combination of a cylinder having common annularly disposed intake and exhaust ports, an inlet chamber and exhaust chamber exteriorly of said cylinder, a vacuum chamber between the piston and the cylinder, a reciprocatable sleeve adapted to place said ports alternately in communication with said inlet and exhaust chambers, means on the piston for causing gases admitted through said ports to assume an annular column along the walls of the cylinder, means whereby burned gases may be exhausted from the cylinder in a central column separate from the incoming column and through the piston and said ports and means controlled by the aforesaid reciprocatable sleeve whereby part of said burned gases may be passed into said vacuum chamber and subsequently discharged therefrom into the exhaust chamber.

4. In a two stroke cycle explosion motor the combination of a cylinder having common inlet and exhaust ports and comprising two concentric members providing an annular space between same, a piston working in said cylinder adapted to cover and uncover

- 5 said ports, an inlet chamber and an exhaust chamber exteriorly of said cylinder, a sleeve reciprocatable in the annular space between the cylinder members said sleeve provided with means for alternately placing said ports in communication with the inlet and exhaust chambers.
- 10 5. In a two stroke cycle explosion motor the combination of a cylinder having common inlet and exhaust ports and comprising two concentric members separated to provide an annular space between same, a piston working in said cylinder adapted to cover and uncover said ports, inlet and exhaust means exteriorly of said cylinder, a sleeve reciprocatable in the space between the cylinder members, a bridge member and a ring on said sleeve adapted to control the passage through said ports in relation to 15 said inlet and exhaust means.
- 15 6. In a two stroke cycle explosion motor the combination of a cylinder having common inlet and exhaust ports and comprising two concentric members separated to provide an annular space between same, a piston working in said cylinder adapted to cover and uncover said ports, inlet and exhaust means exteriorly of said cylinder a sleeve reciprocatable in the space between 20 the cylinder members, and adapted to control said ports in relation to the inlet and exhaust means, a vacuum chamber between the piston and one of the cylinder members
- 25 and coöperating means in the cylinder members piston and sleeve whereby part of the 35 exhaust gases in the cylinder may be passed through said ports into the vacuum chamber and subsequently discharged from said chamber to the exhaust means.
- 30 7. In a two stroke cycle explosion motor 40 the combination of a cylinder having common inlet and exhaust ports extending through its wall and auxiliary exhaust channels formed in its wall, a piston working in said cylinder adapted to cover and 45 uncover said ports and provided with channels adapted to communicate with said auxiliary exhaust channels, a vacuum chamber between the piston and cylinder adapted 50 for communication with said piston channels, an annular rib on the inner end of the piston adapted to deflect gases entering through the aforesaid ports and the piston having further channels in its head within 55 said rib adapted to communicate with said ports or with said auxiliary exhaust channels for discharge of burned gases directly through said ports or to the vacuum chamber.
- 35 In witness whereof I have signed this 60 specification in the presence of two witnesses.

FRANÇOIS PILAIN.
